UNITED STATES PATENT OFFICE.

JOHN GOOD, OF BROOKLYN, NEW YORK.

FPLIER-SPINDLE.

1,191,960.

Specification of Letters Patent. Patented July 25, 1916.

Application filed January 8, 1916. Serial No. 70,899.

To all whom it may concern:

Be it known that I, JOHN GOOD, a citizen of the United States, residing in Brooklyn, county of Kings, and State of New York, 5 have invented the following described new and useful Improvements in Flier-Spindles.

The invention relates to spindles for long-line spinning or twisting machines, such as described in my application filed September 10 13, 1910, Serial No. 581,748, wherein are disclosed certain features in relation to such spindles which are also preferably incorporated in the structure shown herein.

The present object is to further improve 15 these spindles, securing a simple, substantial and relatively light construction, easy to manufacture and adapted to utilize the principle of balanced masses set forth in my said prior application, and especially to 20 produce a spindle in which the operation of threading up can be accomplished with rapidity.

In the accompanying drawings: Figure 1 is a view, partly in side elevation and partly 25 in longitudinal section, of the spindle, with its hauling-off mechanism and flier, and the associated bobbin and bobbin spindle; Fig. 2 is a view, also partially in elevation and partially in longitudinal section, taken at a 30 different angle from Fig. 1; and Fig. 3 is a cross-section on the line III of Fig. 1.

The body of the spindle is a substantially straight shaft 1, which, as a matter of design, may vary in cross-sectional area and 35 shape at different points in its length. Its separated portions 2 and 3, adjacent the ends are formed as journals to turn in the bearings 4 and 5, which are carried by the fixed framework of the spinner, not shown. 40 The end portion of the shaft comprising the journal 2 is tubular and affords an internal bearing for an independently driven yarn-tube 6, which projects beyond the bearing 4 and beyond the end of the spindle and is 45 there provided with a gear 7 whereby it is rotated independently and at a speed differing from that of the spindle, which is driven by a pulley 8 mounted adjacent the journal 2. The portion of the shaft constituting the 50 other journal 3 is of larger diameter than the journal 2 and is enlarged outside the bearing 5 to form an end thrust shoulder 9 and a face plate or flange 10, to which latter the base of a can flier is firmly bolted or 55 otherwise secured.

Intermediate its journal portions and the

supporting bearings, the shaft carries the hauling-off mechanism which comprises main and auxiliary capstans 12 and 13, each mounted to revolve on an axis intersecting 60 and transverse to the axis of the spindle. As in my prior application aforesaid, the capstan members are constructed so as to have equal portions of their mass disposed at opposite sides of the axis of the spindle, 65 whereby the benefits of high speed operation may be realized, as there fully explained. The capstans proper, however, and their counterbalancing elements are at opposite sides of the spindle body, that is to 70 say, on opposite sides of the immediate supporting portion of the spindle, which is in line with the journal portions instead of offset therefrom as in my prior construction.

The capstan 12 is fixed on an axle 14 75 which is journaled in a transverse bearing bored in the spindle body and carries at its opposite end a bevel gear 15, which is dished or crowned in order that its teeth may mesh with the teeth of a bevel pinion 16 on the 80 inner end of the yarn-tube 6, the engagement of the toothed members being made possible by a clearance groove in the shaft at this point, as will be seen in Fig. 3. The counter-balance for the auxiliary capstan 13 85 comprises a cap-like washer 17 interposed between the nut 18 on the end of the capstan axle 19 and a boss 20 on the spindle, it being understood, of course, that the exact mode of obtaining balance of the hauling- 90 off masses is not essential to the invention.

The sliver which enters through the tube 6, on the dot-and-dash line indicated, passes beyond this tube through a passage 21 in the interior of the shaft, the said passage 95 bearing off obliquely or at a gentle curvature from a general longitudinal direction, in order to conduct the sliver in a substantially straight-line path to a lateral, obliquely-facing outlet 22, between the axes of the two 100 capstans and substantially opposite the grooved periphery of the auxiliary capstan 13, to which the incoming stretch of yarn directly extends. Thence the yarn is trained back to the main, or positively driven, capstan 12, and thence back and forth between the two for a suitable number of passes, according to the number of yarn grooves provided therein, after which it is trained over an external guide pulley 23, adjacent and at 110 the inner side of the bearing 5, and between the hauling-off mechanism and the flier. This

guide is counter-balanced like the capstan 13, having a stem 24 which is inserted through a diametrical hole in the spindle and provided at the other side thereof with 5 a cap or washer 25 and nut 26. From the guide button 23 the yarn passes through a transverse and straight passage 27 extending obliquely through the journal portion 3, with its inlet end at the inner side of the 10 bearing 5 and its exit end at the outer side thereof. The yarn may pass through this hole or passage without contact with the spindle direct to a guide-pulley 28 on the outside and near the base of the flier, having thus passed in a direct line from an 15 external guide on the spindle across the spindle axis and its journal-bearing to an external guide on the flier. The yarn is next trained over another external pulley 29, near 20 the open end of the flier, and thence passes inward to the bobbin 30, the guides 28 and 29 on the flier being preferably in skewed relation as shown in order to secure the advantages set forth in my prior application 25 before mentioned. The bobbin it will be understood, is traversed by suitable mechanism, not necessary to illustrate, on the bobbin spindle 31, one end of which finds a terminal bearing at 32 in the end face of the 30 flier spindle.

The mounting of the yarn tube 6 in the feeding-in end of the flier spindle, includes a bushing or internal sleeve 33, which is threaded as shown at 34 to the interior of 35 the outer end of the tubular portion of the spindle body, the outer end of this bushing having a flange 35 in abutting relation to the extremity of the spindle, and its inner end preventing outward axial movement of 40 the pinion 16 and therefore of the yarn tube.

It will be evident that the through passage 27 together with the external location of the pulleys and the fact that there need be but one direction-changing guide on the 45 spindle between the hauling-off mechanism and the flier, greatly increase the ease and quickness with which the threading operation may be performed. In this connection it is to be observed that the course of the 50 yarn from the inlet end of the yarn tube 6 to the lateral outlet 22 is substantially a straight one, and that the capstans are wholly exposed and devoid of adjacent obstacles to the hand or yarn in threading, 55 these being matters of much practical importance to the operator, in respect to the time saved and the wear on the machine, by the yarn, and the wear on the yarn by the machine.

60 What I claim as new is:—

1. A spindle of the character described, comprising a straight shaft constituting the spindle body, having separated journal portions, capstans carried laterally by the 65 straight shaft portion between the journal

portions thereof, with their axes transverse to the axis of the shaft, a yarn inlet through one of the journal portions and a passage leading therefrom through the side of the shaft to permit the yarn to pass to the capstans. 70

2. A spindle of the character described, comprising an approximately straight shaft having separated journal portions, capstans carried laterally by the straight shaft portion between the journal portions thereof, with their axes transverse to the axis of the shaft, one of said journals being tubular for the entrance of the sliver, and a passage leading from said tubular journal 75 obliquely through the adjacent portion of the shaft to a lateral outlet, enabling the yarn to pass substantially directly to one of the capstans.

3. A spindle of the character described, comprising a shaft bearing hauling-off capstans mounted to revolve on transverse axes separated longitudinally of the shaft and having a yarn entrance through its end terminating in a lateral outlet between the axes 80 of the capstans.

4. A spindle of the character described, comprising an approximately straight shaft having a laterally projecting capstan revolvably mounted on a transverse axis on its 85 straight shaft portion, and further provided with an oblique passage for conducting the 90 yarn to the capstan.

5. In a long-line spinner, a live spindle having spaced journal portions rotatable in 100 bearings and carrying a flier at one end outside the adjacent bearing and being substantially straight between its bearings, a yarn tube within its other journal portion, and hauling-off mechanism on the said straight 105 shaft portion comprising laterally projecting capstans revoluble on transverse axes, the said shaft being formed with a yarn passage leading obliquely from the inner end of the yarn tube to a lateral outlet whence the 110 yarn passes to the hauling-off mechanism.

6. In a spinning or twisting machine, a flier spindle, and hauling-off capstans thereon mounted on axles disposed transversely to the axis of the spindle, the spindle being 115 provided with a yarn entrance through its end extended obliquely in a general longitudinal direction past the axle of one of the capstans and terminating in a lateral outlet between the axes of the capstans. 120

7. A flier spindle comprising a shaft and hauling-off mechanism including a capstan having an axle journaled transversely in the shaft, the said shaft being formed with an interior passage leading from an inlet at 125 one end past the said axle at one side thereof to an outlet whence the yarn passes to the hauling-off mechanism.

8. In a spinning or twisting machine, a flier spindle comprising a shaft carrying a 130

ffier at one end, an independently driven 5 yarn tube within its other end, main and auxiliary capstans mounted to revolve on transverse axes on the intermediate portion 10 of the shaft, and gearing between the main capstan and the yarn tube, the said shaft being formed with a passage in its interior leading obliquely lengthwise from the yarn tube to a lateral outlet whence the yarn 15 passes to the auxiliary capstan.

9. A flier spindle carrying a flier at one end and hauling-off mechanism intermediate its ends and formed adjacent the flier with a passage extending completely through it 15 from side to side for conducting the yarn from the hauling-off mechanism to the flier.

10. In a spinning or twisting machine, the combination of a flier spindle comprising a substantially straight shaft having a yarn 20 inlet through its end remote from the flier and an internal inclined passage for conducting the yarn from the said entrance to a lateral outlet, and hauling-off mechanism comprising capstans at one side of the spindle shaft having axles passed transversely 25 through the same intersecting its axis and provided at the opposite side of the shaft with counter-balancing parts approximately equal in mass to the capstans.

11. A flier spindle comprising a shaft having a tubular end, an independently driven tube therein provided with a pinion, the said shaft being provided with a lateral opening adjacent said pinion and with a 35 yarn passage extending lengthwise and obliquely beyond the tube, a capstan at one side of the shaft having an axle passed transversely through the same, and a gear on the said axle at the opposite side of the 40 shaft engaging said pinion through said opening.

12. A flier spindle having hauling-off mechanism and a flier, an external guide to which the yarn passes from the hauling-off 45 mechanism, and a diagonal through passage for permitting the yarn to pass from said guide to the flier.

13. A flier spindle carrying hauling-off mechanism and a flier, and having a journal 50 portion between the two, the said journal portion being formed with a diagonal yarn passage extending through it.

14. In a spinning or twisting machine, the combination of a spindle carrying hauling- 55 off mechanism and a flier, an external yarn

guide on the spindle between the hauling-off mechanism and the flier, and another yarn guide on a laterally remote portion of the flier, the spindle being formed adjacent the flier with a substantially straight diagonal 60 through passage for the yarn.

15. In a spinning or twisting machine, the combination of a flier spindle, a flier on the end thereof provided with external yarn guides, capstans mounted on the spindle to 65 revolve about axes transverse to the axis of the spindle, and an external yarn guide on the spindle adjacent the flier, the portion of the spindle between the said yarn guide and the flier being formed with a passage to conduct the yarn in a direct path from the guide on the spindle to an external guide on the flier.

16. In a spinning or twisting machine, the combination of a spindle having spaced 75 bearing portions turning in suitable bearings, a flier on one end of the spindle provided with yarn guides, hauling-off capstans mounted on transverse axes on the spindle between its bearings, and an external 80 yarn guide on the spindle between the hauling-off capstans and the flier, the spindle being provided with a yarn entrance extending lengthwise through its end portion remote from the flier and extended at a 85 gentle lateral inclination to an outlet approximately in line with one of the capstans, and the portion of the spindle between the said external yarn guide and the spindle being formed with a diagonal 90 through passage having its entrance and exit ends at opposite sides of the adjacent bearing respectively.

17. In a spinning or twisting machine, the combination with a flier spindle having a 95 journal portion adjacent its flier end provided with a diagonal through yarn passage, of an external yarn guide on the spindle adjacent the inlet end of said passage, the said guide having a shank passing transversely 100 through the spindle and provided with a counterbalancing part at the opposite side thereof.

18. A spindle of the character described having an oblique and straight yarn passage 105 between the hauling-off mechanism and the flier.

In testimony whereof, I have signed this specification.

JOHN GOOD.
